UNITED STATES PATENT OFFICE

2,348,513

HEATER FOR FLUIDS

Marion W. Barnes, Chicago, Ill., assignor to Universal Oil Products Company, Chicago, Ill., a corporation of Delaware

Application November 16, 1942, Serial No. 465,704

4 Claims. (Cl. 122—356)

This is a continuation-in-part of my co-pending application Serial No. 364,832, filed November 8, 1940, now Patent No. 2,324,553, granted July 20, 1943.

The invention is directed to an improved form of heater which will be found particularly advantageous for heating fluid hydrocarbons to the high temperatures required for their conversion. However, the invention is not restricted to this particular use, since it will find numerous other advantageous applications.

The heater herein provided is of the general type now well known in the art, wherein flames and hot gases resulting from the combustion of fuel are passed upwardly or downwardly over the surface of spaced, substantially vertical refractory walls, heating the same to a highly radiant condition, heat being transmitted by radiation from the refractory walls and directly from the flames and hot gases to a fluid conduit disposed centrally between said walls. In the improved form of heater herein provided, said fluid conduit comprises three vertically parallel rows of horizontally disposed tubes, the tubes in adjacent rows being so arranged that the outer side of each of the tubes in the two outside rows receives heat directly by radiation from the adjacent refractory wall and the flames and hot combustion gases passing thereover, while opposite sides of each of the tubes in the middle row receive heat by radiation from the flames, hot gases and refractory walls at a reduced rate due to the partial shielding effect of the tubes in the two outer rows. With this arrangement, by varying the sequence of flow through the three rows of tubes and/or by varying firing conditions on opposite sides of the fluid conduit, a wide variety of heating curves is obtainable and the desired flow may be selected to suit the requirements of the particular type of fluid undergoing treatment.

In the accompanying diagrammatic drawing Fig. 1 is an elevational view, shown principally in section, of one specific form of the heater provided by the invention.

Figs. 2, 3, and 4 of the drawing are flow diagrams representing three of the many specific manners in which the tubular fluid conduits of the three-row tube bank 9 of Fig. 1 may be interconnected.

Referring to Fig. 1, the single cell down-fired heater here illustrated has a foundation indicated at 1 on which a plurality of steel columns 2, supporting steel beams 3, are mounted. The steel framework supports the refractory shapes of side walls 4 and 5 and roof 6 in any conventional manner not pertinent to the invention and not here illustrated.

The substantially vertical portions of the side and end walls of the heater, which latter do not

appear in this particular view, define combustion and radiant heating zones 7 and 8 which are disposed between the respective side walls 4 and 5 and fluid conduit 9. The latter is located substantially midway between walls 4 and 5 and comprises three vertically parallel rows of horizontally disposed tubes 10 with the adjacent tubes in the several rows arranged in staggered formation, as illustrated.

At their lower ends, the side walls 4 and 5 slope inwardly to connect with the side walls 11 and 12 of fluid heating zone 13 disposed beneath and in substantially vertical alignment with fluid conduit 9. Another fluid conduit 14 comprising, in the case here illustrated, a plurality of superimposed horizontal rows of horizontally disposed tubes 15 is located within fluid heating zone 13.

A row of firing ports 16 is provided in the roof of the furnace adjacent each of the side walls 4 and 5 and corresponding rows of burners 17 supply fuel and air to the combustion and heating zones 7 and 8 through firing ports 16. The burners and firing ports are so arranged that flames and hot gases resulting from combustion of the fuel are directed in a substantially continuous sheet downwardly over the refractory surfaces of walls 4 and 5, heating the latter to a highly radiant condition and keeping fluid conduit 9 out of the direct path of flow of the flames and hot combustion gases.

The tubes of fluid conduit 9 receive heat by direct radiation from the flames, hot combustion gases and radiant side walls of the heater. Since the tubes in the central row of bank 9 are partially shielded by the tubes in the two outer rows, they are subjected to less intense heating than the tubes in the outer rows and, by varying the sequence of flow of the fluid undergoing heating through the rows of bank 9 and/or by varying the firing conditions employed on opposite sides of the heater, a wide variety of heating curves is obtainable and the type of heating curve obtained may be selected to suit the requirements of the particular type of fluid undergoing treatment.

The combustion gases, which have given up a major portion of their radiant heat to the tubular elements of bank 9, pass from the combustion and heating zones 7 and 8 through fluid heating zone 13 to flue 18 wherefrom they may pass to a suitable stack, not illustrated. The combustion gases flowing through zone 13 intimately contact the tubes of bank 14 and supply heat to the latter and to the fluid passing therethrough.

Referring now to Fig. 2, this figure illustrates one manner in which the banks of tube 9 and the various vertical rows of tubes in this bank may be connected. In this particular case, one stream of fluid to be heated is supplied to the up-

permest tube of the central row and passes downwardly in series through the adjacent tubes of this row to be discharged from the lowermost tube thereof. A separate stream of fluid to be heated is divided into two streams of substantially equal volume, one of which is supplied to the lowermost tube of one of the outer rows, while the other is supplied to the lowermost tube of the other row. These streams are directed upwardly in series through the adjacent tubes of the outer rows and are commingled, following their discharge from the uppermost tubes there-
of.

The general direction of flow of the fluids through tube bank 9 may be reversed to that illustrated in Fig. 2, the central stream flowing upwardly through the central row of tubes and the outward streams flowing downwardly through the outer row of tubes. The invention also contemplates a flow otherwise like that illustrated in Fig. 2, with all three streams passed either upwardly or downwardly through the bank.

In Fig. 3, a single stream of fluid is passed upwardly in series through the tubes of the central row and a separate stream of fluid is passed first upwardly in series through the tubes of the right-hand outer row and then downwardly in series through the tubes of the right-hand outer row. The general direction of flow of either or both streams may, when desired, be reversed to that illustrated in Fig. 3. Also, when desired, the flow of the second named stream may be in a general downward direction through the other row to which it is first supplied and upwardly through the outer row.

In Fig. 4 a single stream of fluid is passed downwardly in series through the tubes of the central row and a separate stream of fluid is passed, first, upwardly in series through the tubes of the right-hand outer row and thence upwardly in series through the tubes of the left-hand outer row. The general direction of flow for either or both streams may also be reversed to that illustrated in Fig. 4, when desired. I also contemplate, first, passing the second named stream upwardly through the left-hand outer row and thence upwardly through the right-hand outer row. It is also within the scope of the invention to employ a flow otherwise similar to that illustrated in Fig. 4 with the second named stream passed in series through the two outer rows and downwardly in each row with either upward or downward flow of the first named stream of fluid through the central row.

The three-row tube bank of the heater herein provided lends itself to numerous other specific flows for a single stream or for separate streams of fluid. Some of the other flows are disclosed in my aforementioned co-pending application Serial No. 364,832 and still others are disclosed in a division thereof filed November 16, 1942, as Serial No. 465,703. However, the present application is directed to a heater of the type disclosed wherein tube bank 9 serves to heat separate streams of fluid, one stream being passed through one row of the bank and the other stream being passed through the other two rows of the bank.

The aforementioned co-pending application Serial No. 364,832 also discloses several specific forms of the furnace structure provided by the invention other than that herein illustrated and above described. It is within the scope of the invention to employ a general flow, such as above mentioned, or any of the several specific flows

above described, in these other specific forms of furnace structures. Various other modifications of the general furnace structure will be apparent to those familiar with the art from the teachings of the invention and may be employed without departing from its broad scope of the invention.

With heaters of the general type herein provided, independent control of the quantity of fuel supplied to the separate combustion and heating zones permits maintaining substantially the same conditions in both zones or employing more severe or less severe conditions in one zone, as compared with those employed in the other. Also, by varying the quantity of excess air supplied to each combustion and heating zone, the heating conditions may be varied from top to bottom of the zone. These alternative firing conditions may be selected to suit requirements with any of the aforementioned flows through the three-row tube bank.

The invention also contemplates spacing the tubes of one or both of the two outer rows of the three-row tube bank on closer or on wider centers than the center to center distance between the adjacent tubes of the central row, so as to either increase or decrease the extent to which the tubes of the central row are shielded by the tubes of the outer rows. The invention also contemplates using smaller or larger diameter tubes in one of the fluid streams than those employed in the other fluid stream passing through the three-row tube bank.

I claim as my invention:

1. A heater for fluids comprising, in combination, refractory side and end walls defining a combustion and heating chamber, a tube bank comprising three vertically parallel rows of horizontal tubes disposed substantially midway between said side walls within said chamber, and means for directing flames and hot gases resulting from the combustion of fuel through said chamber over the inner surfaces of said refractory side walls in a substantially vertical direction and in radiant heat transmitting relation to said tube bank, said bank being constructed and arranged for the passage of a single stream of fluid in series through the outer two rows of the bank, and for the passage of another stream of fluid through the central row of the bank.

2. A heater for fluids comprising a heating chamber having refractory side walls, a tube bank within said chamber disposed substantially midway between the side walls thereof, said bank comprising two vertically parallel outer rows of tubes and an intermediate row of tubes between said outer rows, adjacent tubes in each of said rows being connected in series, means for passing hot combustion products through said chamber on opposite sides of the tube bank, a common fluid supply line for said outer rows and means for passing fluid from said line through both of the last-named rows, and an independent fluid supply line communicating with said intermediate row of tubes.

3. The heater as defined in claim 2 further characterized in that said outer rows of tubes are constructed and arranged for the parallel flow therethrough of fluid from said common supply line.

4. The heater as defined in claim 2 further characterized in that said outer rows of tubes are connected in series with each other and with said common supply line.

MARION W. BARNES.
